UNITED STATES PATENT OFFICE.

THOMAS C. WILLIAMS, OF EAST BAKERSFIELD, CALIFORNIA.

SASH LIFTER AND LATCH.

Application filed January 13, 1926. Serial No. 80,931.

My invention relates to windows, and more particularly to a set of appliances associated with the upper and lower sashes of said window whereby said upper sash may be expeditiously raised and lowered, and when in raised position, effectively fastened in such position.

As is well known, due to changes in weather, the upper sash of a window especially sticks, so that frequently it is impossible to lower the same without requiring the services of a carpenter. By the use of my invention this objectionable, and sometimes expensive feature is effectively eliminated, a handy and effective means being provided not only for raising and lowering the upper sash of a window, but also providing a thoroughly effective means for fastening the window when closed, means being provided for positioning the device in such a manner that it will not interfere with the lower sash, it being possible to raise and lower both sashes by hand, if desired.

It accordingly is an object of my invention to provide a novel form of sash lifter and fastening device in which an anchoring member or device is associated in any preferred manner and at any convenient position with the upper sash of a window, said anchoring device having hinged thereto an elongated member with which a lifting device is detachably associated, the lower sash being equipped with a locking device in the shape of a resilient appliance adapted to coact with said fastening device to hold the window in locked position.

A further object of my invention is to provide a novel form of device which is inexpensive to manufacture, thoroughly effective and reliable in operation, composed of a minimum number of parts, capable of being quickly and easily associated with the parts to be operated and fastened, and one which will thoroughly and reliably effect the objects intended.

Further objects and advantages of my invention will become more apparent as the description thereof proceeds.

Reference is had to the accompanying drawings, in which similar reference characters denote similar parts. In the drawings,

Fig. 1 is an elevational view of a window in closed position, and with my novel device positioned thereon, the window being fastened,

Fig. 2 is a similar view showing the upper sash lowered,

Fig. 3 is a view similar to Fig. 2, but showing the upper sash in fully lowered position, and illustrating the manner in which the lifting device may be positioned between the two sashes, and both sashes capable of being raised and lowered without interfering with said device,

Fig. 4 is a view similar to Fig. 1, but showing the device swung out of the way, and

Fig. 5 is a top plan view on an enlarged scale of the fastening device.

Describing my invention more in detail, I provide an anchoring member or device 1 adapted to be associated with the upper sash U of a window W, and positioned thereon in any convenient place, but preferably centrally thereof, and secured thereto by any preferred means such as screws 2, though any means may be substituted therefor.

Associated with the anchoring member or device 1, which may be countersunk within the framework of the sash U, or may merely be screwed thereon, is an elongated member 3 of any preferred configuration, and equipped with a projection 4 of any preferred shape, and from which projection an extension 5 is adapted to project. As will be obvious, these parts may form one integral construction, or they may be associated in any manner preferred. The elongated member 3 is preferably hinged to the anchoring member 1 by means of a suitable hinge 6 of any preferred construction, so that it will be possible to swing the elongated member 3 toward and away from the sash U.

The lifting device L may in practice take any form found desirable, it being formed of wood, metal, or any other suitable material, thickness and shape. Either integral with the lifting device L, or associated therewith in any manner preferred, is an eye 7, or other device whereby the lifting device L may be detachably associated with the extension 5. It will of course be understood that if preferred the lifting device L may be permanently associated with the extension 5, which extension also may be omitted, and the lifting device L associated with the projection 4, as in practice preferred.

Associated with the lower sash 1 is a fastening device indicated generally by the numeral 8 and shown more particularly in Fig.

5. This fastening device preferably comprises a securing device in the shape of a plate 9 of any shape, and constructed of any preferred material, securing means such as 5 screws or other devices 10 being used to secure the plate 10 to the top of the lower sash 1, and preferably on the middle part thereof. Either integral with the plate 9, or associated therewith in any manner preferred, 10 is a fastening clamp 11 preferably of U-shape, and equipped with resilient side members 12, flared, as shown more particularly in Fig. 5, said flared portions being adapted to be swung apart so that the fastening device L may be resiliently held therebetween in order that the window may effectively be locked.

The operation of my invention should now be clear. To lower the sash U, all that 20 is necessary to do is to pull the lifting device 1 outwardly from between the flared portions 12, after which the sash U may be quickly and expeditiously lowered by pulling on said lifting device. Said lifting device 25 may be positioned as shown on Fig. 2, or it may be swung to the positions shown in Figs. 3 and 4, and hence out of the way, so that the upper sash may be raised and lowered by hand, as for example when the windows are being washed. To raise the 30 upper sash, when the device is in the position depicted in Figs. 3 and 4, the lifting device L is grasped, and the elongated member 3 swung into the position depicted in Fig. 2, after which the lifting device L is pushed upwardly, the sash U being closed, after which the lifting device L is pushed home into the fastening device 11, securely fastening the window.

40 While I have thus described my invention with great particularity, it will be clear that the same may be modified throughout a wide range. I therefore do not purpose to be limited to the exact details of construction 45 shown and described, but reserve the right in practice to make any and all modifications thereof that fall within the scope of the appended claims.

I claim as my invention:

1. A combined sash lifter and latch for 50 windows comprising an anchoring device positioned on said sash, a sash lifting device, a swinging member associated with said anchoring device and said lifting device whereby said lifting device may be swung toward 55 said sash so that said sash may be raised or lowered, and a keeper associated with said window for receiving one end of said lifting device for fastening said window.

2. In a device of the class described, an 60 anchoring device comprising a stationary element adapted to be fastened to a support and a movable element adapted to be swung toward and away from said stationary element, a lateral projection on one end of said 65 movable element, and a lifting device detachably associated with said projection whereby said support may be raised or lowered.

3. In a window, in combination with the 70 upper and lower sashes, a pair of relatively 75 movable elements, one of which is secured to said upper sash, and the other adapted for movement toward and away from said sash, and a lifting device associated with said movable element whereby said lifting device may be swung bodily with said movable element so that said lifting device may be positioned between said sashes so that either 80 may be raised or lowered without interfering with said lifting device.

4. In a window, in combination with the upper and lower sashes thereof, an anchoring device associated with said upper sash, said anchoring device comprising a plate, an elongated member hinged to said plate, an extension projecting laterally from said elongated member, a lifting device detachably associated with said extension, and a fastening device associated with said lower 90 sash whereby said lifting device may coact with said fastening device to fasten said window.

In testimony whereof I have signed my name to this specification.

THOMAS C. WILLIAMS.
